1. A device for use with a boot or overshoe, comprising a flexible tube having a lower end and an upper end, the lower end being closed and having a valve which is normally held in closed position to prevent the entrance of mud or dirt into the tube, the tube being secured to the boot or overshoe, the upper end of the tube being provided with an adapter which is secured to the boot or overshoe, the adapter being provided with a longitudinal passage extending therethrough, the tube being secured to the boot or overshoe in such manner that the tube is in communication with the longitudinal passage.

VACUUM RELIEVING ATTACHMENT FOR BOOTS AND OVERSHOES

Ralph E. Marks, El Dorado Springs, Mo.

Application March 27, 1945, Serial No. 585,073

4 Claims.

(Cl. 36—1)

2

The present invention relates to new and useful improvements in attachments for boots and overshoes, and has for its primary object to relieve the vacuum or suction effect created under the sole of the boot when walking in mud or other soft places.

It is well known that when wearing boots or overshoes, while walking in mud or other soft places, wherein the sole of the boot sinks into the mud, there is a tendency to create a vacuum or suction under the sole of the boot which has the effect of pulling the boot from the foot of the wearer.

In order to overcome this objectionable practice, I provide a vent tube extending from a point in front of the heel of the boot upwardly on the outside thereof and providing the lower end of the tube with a suction-operated flap valve which is normally held in closed position to prevent the entrance of mud or dirt into the lower end of the passage and which is responsive to the suction or vacuum action created on the under side of the boot to open the valve and thus break the vacuum, and thus facilitate lifting of the boot from the mud.

An important object of the present invention is to provide an attachment of this character adapted for use upon either high boots or overshoes.

A further object of the invention is to provide an attachment of this character of simple and practical construction, which is efficient and reliable in use, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a side elevational view, with parts broken away and shown in section.

Figure 2 is a sectional view through the heel of the boot taken substantially on a line 2—2 of Figure 1.

Figure 3 is an enlarged longitudinal sectional view of the adapter at the upper end of the tube for use with either high boots or when the upper end of the boot is rolled downwardly.

Referring now to the drawing in detail, wherein for the purpose of illustration I have disclosed a preferred embodiment of the invention, the numeral 5 designates a boot of conventional construction and including a sole 6 and heel 7.

5 A longitudinally extending passage 8 is formed in the heel, the front edge of the heel being formed with a recess 9 with which the front end of the passage 8 communicates.

10 A flexible rubber flap valve 10 has its end portions cemented or otherwise secured in the sides of the recess 9 while the intermediate portion of the valve is free and extends transversely over the front end of the passage 8 for closing the latter.

15 The passage 8 extends upwardly and rearwardly to the rear end of the heel and has a flexible rubber tube 11 attached at its lower end to the rear end of the passage 8, the tube 11 extending upwardly behind the boot 5 and suitably secured thereto, as by cementing, vulcanizing or the like.

20 The upper end of the tube 11 is free and is provided with a nipple 12 which forms an adapter having its outer end 13 removably inserted in an upper tubular section 14 of rubber or the like secured to the rear of the boot 5 at its upper portion, the upper end of the tube section 14 being open.

25 A loop 15 is provided at the upper rear portion of the boot 5 by means of which the boot may be pulled on the foot of a wearer and when the upper end of the boot is pulled in its uppermost position, as shown in Figure 1 of the drawing, the adapter 12 is inserted in the lower end of

30 the tubular section 14.

When walking in mud or other soft places, a vacuum or suction is created under the arch portion 6 of the sole of the boot and the initial lifting action of the boot from the mud results in the vacuum exerting a pulling force on the flap valve 9 to open the lower end of the passage 8, whereby air is admitted under the sole of the boot to break the vacuum thereunder and thus facilitate the lifting of the boot from the mud.

35 40 When the upper end of the boot is rolled downwardly, the adapter 12 is removed from the tube section 14 and is inserted in a cloth or other flexible loop 16 secured preferably to the outer face of the inner side of the boot intermediate its upper and lower ends, as shown by the dotted lines in Figure 1. The flexible loop 16 thus supports the adapter 12 so that the upper free end of the tube 11 is prevented from flapping while walking.

45 50 From the foregoing description, it will be apparent that the device may be worn without inconvenience and greatly facilitates the walking in mud and other soft places where a tendency is created to pull the boot from the foot of the wearer.

It is believed the details of construction, manner of use and advantages of the device will be readily understood from the foregoing without further detailed explanation.

Having thus described the invention, what I claim is:

1. An attachment for footwear including a heel having an air passage extending from its front to its rear edge, a flap valve closing the front end of the passage, and an upwardly extending tube connected to the rear end of said passage, said valve being normally closed and responsive to suction created under the footwear to open the valve and admit air under the bottom of the footwear.
2. An attachment for footwear and including an air passage leading from below the bottom of the footwear and in front of the heel to an upper portion thereof, and a normally closed valve control means for the lower end of the passage and responsive to vacuum created under the footwear to open the valve control means so as to admit air at atmospheric pressure to the under side of the footwear for breaking the vacuum.

3. An attachment for footwear including a heel having an air passage extending from its front to its rear edge, a flap valve closing the front end of the passage, and an upwardly extending tube connected to the rear end of said passage, said valve being normally closed and responsive to suction created under the footwear to open the valve and admit air under the bottom of the footwear, and means carried by the

5 10 footwear above the heel for securing the upper end of the tube in a stationary position.

4. An attachment for footwear including a heel having an air passage extending from its front to its rear edge, a flap valve closing the front end 15 of the passage, and an upwardly extending tube connected to the rear end of said passage, said valve being normally closed and responsive to suction created under the footwear to open the valve and admit air under the bottom of the footwear, and means carried by the 20 footwear at vertically spaced points above the heel for securing the upper end of the tube in a stationary position.
